UNITED STATES PATENT OFFICE.

WILLIAM J. CAMPBELL, OF INDIANAPOLIS, INDIANA, ASSIGNOR TO AMERICAN SLICING MACHINE COMPANY, OF CHICAGO, ILLINOIS, A CORPORATION OF NEW YORK.

SLICING MACHINE.

Application filed April 13, 1928. Serial No. 289,684.

My invention relates to a slicing machine and particularly to a slicing machine having a rotary knife and means for driving it, of the type wherein a work supporting carriage is provided and means for guiding it across the face of the knife. One object of my invention is to furnish a support for the slices which are being cut. The presence of such a support, which holds the slice in the plane of the larger piece from which it is cut, insures a uniform and efficient severance of the slices from the piece, prevents ragged slices, and prevents slices from being partially severed. A clear, complete cut is insured. Another object of my invention is to prevent the slices from falling into the space between the gauge plate and the carriage, and to insure that each slice cut shall pass through the space between gauge plate and knife to the trough or receiving means. Other objects will appear from time to time in the course of the specification and claims.

I illustrate my invention more or less diagrammatically in the accompanying drawings, wherein—

Figure 1 is a front elevation;

Figure 2 is a section on the line 2—2 of Figure 1;

Figure 3 is a section on the line 3—3 of Figure 1;

Figure 4 is a view similar to Figure 1 illustrating a variant form of the same construction;

Figure 5 is a section on the line 5—5 of Figure 4;

Figure 6 is a section on the line 6—6 of Figure 5; and

Figure 7 is a transverse section through a further variation of my device.

Like parts are indicated by like symbols throughout the specification and drawings.

Referring first to Figures 1 to 3, A indicates any suitable slicing machine base member having the ground engaging supports or studs A¹. B generally indicates any suitable housing member or body upwardly projecting therefrom having associated therewith a face plate B¹, normally fixed in position and a gauge plate B² which may be moved toward and away from the plane of the knife as for example by rotation of the knob B³. I do not wish to be limited to any particular means for imparting movement to the gauge plate but I have herein shown lugs B⁴ on the rear of the gauge plate, levers

or arms B⁵ pivoted thereto, themselves pivoted as at B⁶, a gear B⁷ associated with one of said levers and a worm B⁸, in mesh therewith and actuated by the knob B³.

C indicates the knife, it being herein shown as recessed in its forward face as at C¹ in order to permit the peripheral portion C² to project outwardly into and slightly beyond the planes of the face plate B¹. It will be understood that the axis of the knife, in the form herein shown, lies in a generally horizontal plane but is tilted slightly from perpendicularity to the face plate B¹, in order to throw one edge of the knife forwardly into the plane of said face plate.

D generally indicates a guide track, herein shown as cylindrical, and mounted at its ends upon the supports D¹. Beneath it is a supplemental track D² herein shown as of rectangular cross-section. D³ indicates a carriage slideable along the track D, provided with a downward extension D⁴ formed to surround the track D² and thus to prevent rotation of the carriage D³ about the track D. D⁵ is any suitable manual handle whereby the carriage may be moved along the track D. D⁶ is any suitable material carrying tray positioned upon the carriage D³. Unless the gauge plate B² is adjusted so far forward as to lie practically in the plane of the cutting edge of the knife C there will be a space between the gauge plate and the carriage plate D⁶. If this space is left open, bits or slices of material may under some circumstances drop therethrough instead of passing through the space between the knife edge C² and the opposed arcuate edge of the gauge plate. In order to render this impossible and to insure that all slices shall pass through such gap I provide a supplemental horizontal ledge or plane surfaced member, to prevent such slices from dropping down between the gauge plate B² and the carrier plate D⁶.

Referring for example to Figures 2 and 3 I illustrate, mounted upon the gauge plate B² a shelf generally indicated as E which includes a portion E¹ engaging and secured to the gauge plate and an outwardly projecting portion E² which closely engages and underlies the edge of the plate D⁶ which may be milled away or thinned as at E³ to receive it. It will be observed from Figure 2 that the ledge E² extends across substantially the entire width of the face plate al-

though its own maximum usefulness is of course adjacent the cutting edge. It is extended to the right, as shown in Figure 2, as at E^4 in order that it may hug the edge 5 of the knife in all positions of normal adjustment of the gauge plate. This extension is shown as having an arcuate edge in order to compensate for the arcuate path which the gauge plate takes when it is adjusted by means of pivoted levers or arms, as shown in Figure 2. It will be understood that if some other adjusting means are employed in which the gauge plate takes a different path, as for example a straight 10 path at an angle to the path of movement of the carriage, the extension E^4 will be properly shaped, in order to hug the edge of the knife.

Referring to the form of Figures 4, 5 20 and 6, I employ a narrow member or shelf G which extends across substantially the entire front of the gauge plate and is secured to the face thereof. Adjacent the knife edge the gauge plate is cut away or slotted 25 as at G^1 and positioned to register with the slot is a fixed meat support G^2 mounted on any suitable bracket or pedestal G^3 . The upper surface G^4 of the support G^2 may be slightly above the level of the upper surface 30 of the angle G , in order that it may register closely with the level of the carriage D^6 , as shown in Figure 6.

The edge of the meat support is preferably inclined or beveled as at G^5 in order 35 to prevent any stoppage or interference of the work or slice as it crosses over and upon the support G^2 . The meat support G^2 is always up against the edge of the carriage and supports the slice and prevents any 40 particle or fringe or portion of the slice from dropping down between the carriage and the knife. The angle G on the gauge plate serves to keep the last slice from falling off the pusher plate.

Referring to Figure 7 I illustrate a form 45 in which the angle H is provided with a portion H^1 underlying the carriage D^6 , as in Figure 3. The angle however terminates at its upper side, at its junction with the 50 gauge plate in an upwardly extending or inclined portion H^2 the upper portion of which lies in the same general plane as the top of the carriage D^6 . The edge of the carriage may be inclined or milled away as 55 at H^3 in order to conform generally to the inclined portion H^2 . This formation of the angle may be employed with either of the forms above described and shown.

It will be realized that whereas I have 60 described and shown a practical and operative device that nevertheless many changes might be made in size, shape, number and disposition of parts without departing from the spirit of my invention. I therefore 65 wish my description and drawings to be

taken as in a broad sense illustrative and diagrammatic rather than as limiting me to my specific showing.

For example whereas I have illustrated means for adjusting the shelf E laterally in 70 relation to the gauge plate B^2 , as for example by the slots E^{10} in the portion E^1 of the shelf and the adjusting screws E^{12} passing therethrough, other lateral adjustment might be employed. Also I may dispense 75 with such adjustment altogether for example by adjusting the gauge plate as a whole toward and away from the knife edge. This adjustment may be necessary in order to compensate for the wear of the knife and 80 to insure that the plate E and its extension E^4 shall hug the knife edge.

The use and operation of my invention are as follows:

In employing a meat or work carriage for 85 supporting the carriage for supporting the work as it is carried across the face of the knife, and in employing the gauge plate against which the work is thrust, whether manually or mechanically, it is important 90 to support the slice while the slice is being cut. Were it possible, which it is not, to have the carriage approach so close to the gauge plate that no interval is left between gauge plate and carriage, there will be no 95 necessity of supporting the slice in the front of the gauge plate. However the mere fact that the gauge plate is adjusted toward and away from the path of the carriage insures that there will be a space 100 between gauge plate and carriage. And furthermore, the increase of the opening between the edge of the gauge plate and the cutting edge of the knife, which determines the thickness of the slice, insures that there 105 will always be a space between carriage, gauge plate and knife at that point, in which the carriage gives no support. I therefore provide a shelf or support which cooperates with the carriage and which is independent, 110 in its supporting function, of the position of the gauge plate.

Referring to Figures 2 and 3 it will be clear that the shelf E will underlie the edge of the carriage at all normal positions of 115 the gauge plate and that therefore no slice or fragment of meat can drop down through the space between carriage and gauge plate.

Even more important is the lateral extension E^4 of the shelf which is formed to hug the cutting edge of the knife at all 120 positions of the gauge plate. This insures that the slice, in course of severance, will be supported up to the instance of its completion.

The support at this point prevents partially completed slices and little tail ends of meat from sliding down around the corner of the carriage and getting between the front of the carriage and the knife.

In view of the frequent practice of using vitreous enamel for carriage and gauge plate the addition of the slice supporting shelf is important. The front of the carriage is necessarily rounded or oval shaped owing to the fact that the enamel will not stick on a sharp corner. This rounding of the parts would tend to provide an opportunity for the escape of small bits of meat, partly completed slices and the like were it not for the employment of the shelf or support.

Also, the shelf, positioned as it is across substantially the entire front of the gauge plate prevents the last slice from falling down between the front of the carriage and the gauge plate.

In the form of Figures 4, 5 and 6 in the place of the angle extending across the entire face of the plate I employ the angle G which extends across the major width of the gauge plate but terminates at the beginning of the cut away portion or slot G¹. Here the task of supporting the slice is taken up by the fixed support G², which supports the slice up to the cutting instant. It is always up against the edge of the carriage and also closely hugs the edge of the knife and supports the slice until its separation from the work is completed. Thus it prevents any fringe of meat from dragging over and prevents the slice or any part of the slice from penetrating or dropping into the space between carriage and knife.

The form of Figure 7 has the advantage of lifting the edge of the work, before the slice is separated, into the plane of support of the body of the work. Referring to Figure 7 it will be observed that when the work is thrust forward, on the carriage, toward the gauge plate, it will engage the inclined portion H² and be lifted up thereby, so that the lower edge of the work, as it abuts against the gauge plate, will lie in the plane of the upper face of the carriage D².

I claim:

1. In a slicing machine having a rotary knife and means for rotating it, a carriage and means for guiding it along a path across the plane of said knife, a gauge plate lying in a plane generally parallel with the path of movement of said carriage, and means for moving it toward and away from said carriage, and a shelf member, outwardly projecting from said gauge plate toward said carriage.

2. In a slicing machine having a rotary knife and means for rotating it, a carriage and means for guiding it along a path across the plane of said knife, a gauge plate lying in a plane generally parallel with the path of movement of said carriage, and means for moving it toward and away from said carriage, and a shelf member, outwardly projecting from said gauge plate toward

said carriage, and underlying the edge of said carriage.

3. In a slicing machine having a rotary knife and means for rotating it, a carriage and means for guiding it along a path across the plane of said knife, a gauge plate lying in a plane generally parallel with the path of movement of said carriage, and means for moving it toward and away from said carriage, and a shelf member, outwardly projecting from said gauge plate toward said carriage, and underlying the edge of said carriage, the edge of said carriage being provided with a thin portion adapted to overlie said shelf.

4. In a slicing machine having a rotary knife and means for rotating it, a carriage and means for guiding it along a path across the plane of said knife, a gauge plate lying in a plane generally parallel with the path of movement of said carriage, and means for moving it toward and away from said carriage, and a shelf member mounted upon and outwardly projecting from said gauge plate toward said carriage.

5. In a slicing machine having a rotary knife and means for rotating it, a carriage and means for guiding it along a path across the plane of said knife, a gauge plate lying in a plane generally parallel with the path of movement of said carriage, and means for moving it toward and away from said carriage, and a shelf member mounted upon and outwardly projecting from said gauge plate toward said carriage, and underlying the edge of said carriage.

6. In a slicing machine having a rotary knife and means for rotating it, a carriage and means for guiding it along a path across the plane of said knife, a gauge plate lying in a plane generally parallel with the path of movement of said carriage, and means for moving it toward and away from said carriage, and a shelf member, outwardly projecting from said gauge plate toward said carriage, and a lateral extension from said shelf formed to hug the edge of the knife at normal adjustments of the gauge plate.

7. In a slicing machine having a rotary knife and means for rotating it, a carriage and means for guiding it along a path across the plane of said knife, a gauge plate lying in a plane generally parallel with the path of movement of said carriage, and means for moving it toward and away from said carriage, and a shelf member, outwardly projecting from said gauge plate toward said carriage, and a lateral extension from said shelf formed to hug the edge of the knife at normal adjustments of the gauge plate, the horizontal contour of the edge opposed to the knife being arcuate.

8. In a slicing machine having a rotary knife and means for rotating it, a carriage

- and means for guiding it along a path across the plane of said knife, a gauge plate lying in a plane generally parallel with the path of movement of said carriage, and means for moving it toward and away from said carriage, and a shelf member, outwardly projecting from said gauge plate toward said carriage, and extending across substantially the entire width of the gauge plate. 45
- 5 10. 9. In a slicing machine having a rotary knife and means for rotating it, a carriage and means for guiding it along a path across the plane of said knife, a gauge plate lying in a plane generally parallel with the path 50 of movement of said carriage, and means for moving it toward and away from said carriage, and a shelf member, outwardly projecting from said gauge plate toward said carriage, and means for adjusting said shelf. 55
- 15 10. 10. In a slicing machine having a rotary knife and means for rotating it, a carriage and means for guiding it along a path across the plane of said knife, a gauge plate lying in a plane generally parallel with the path 60 of movement of said carriage, and means for moving it toward and away from said carriage, and a shelf member, outwardly projecting from said gauge plate toward said carriage, and means for adjusting said shelf. 65
- 20 15. 11. In a slicing machine having a rotary knife and means for rotating it, a carriage and means for guiding it along a path across the plane of said knife, a gauge plate lying in a plane generally parallel with the path 70 of movement of said carriage, and means for moving it toward and away from said carriage, and a shelf member, outwardly projecting from said gauge plate toward said carriage, and means for adjusting said shelf. 75
- 25 20. 12. In a slicing machine having a rotary knife and means for rotating it, a carriage and means for guiding it along a path across the plane of said knife, a gauge plate lying in a plane generally parallel with the path 80 of movement of said carriage, and means for moving it toward and away from said carriage, and a shelf member, outwardly projecting from said gauge plate toward said carriage, and means, interposed between shelf and gauge plate, for adjusting said shelf toward and away from the knife edge. 85
- 30 35. 13. In a slicing machine having a rotary knife and means for rotating it, a carriage and means for guiding it along a path across the plane of said knife, a gauge plate lying in a plane generally parallel with the path 90 of movement of said carriage, and means for moving it toward and away from said carriage, and a shelf member, outwardly projecting from the plane of said gauge plate toward said carriage. 95
- 35 40. 14. In a slicing machine having a rotary knife and means for rotating it, a carriage and means for guiding it along a path across the plane of said knife, a gauge plate lying in a plane generally parallel with the path 100 of movement of said carriage, and means for moving it toward and away from said carriage, and a shelf member, outwardly projecting from said gauge plate toward said carriage, and underlying the edge of said carriage, the inner edge of said shelf member, as it abuts against the gauge plate, extending upwardly into the plane of the upper face of the carriage. 105
- 40 45. 15. In a slicing machine having a rotary knife and means for rotating it, a carriage and means for guiding it along a path across the plane of said knife, a gauge plate lying in a plane generally parallel with the path 110 of movement of said carriage, and means for moving it toward and away from said carriage, and a shelf member, outwardly projecting from said gauge plate toward said carriage, and underlying the edge of said carriage, the inner edge of the shelf member, where it abuts against the gauge plate being inclined upwardly into the plane of the upper face of the carriage, the inner edge of the carriage being formed to conform generally to said upwardly inclined portion of the shelf. 115
